E. A. HAAS ET AL

WATER COOLER AND REFRIGERATING APPARATUS

Original Filed July 5, 1923

UNITED STATES PATENT OFFICE.

EDWARD A. HAAS, OF LOS ANGELES, CALIFORNIA, AND MACK POSEY, OF SAND SPRINGS, OKLAHOMA.

WATER COOLER AND REFRIGERATING APPARATUS.

Application filed July 5, 1923, Serial No. 649,551. Renewed January 25, 1927.

This invention relates to water coolers and refrigerating apparatus.

The prime object is to provide a device for thoroughly and rapidly cooling water for drinking purposes, the supply of the latter being under constant pressure from the city mains, to maintain the receptacle full at all times, no matter how fast the cooled water may be drawn therefrom.

Another object is to provide a cooling device having a water receptacle which is hermetically sealed to prevent any contamination thereof from the outside, and which may be readily and thoroughly cleansed at any time to maintain the same in a sanitary condition.

A further object is to provide means for connecting the cooler to an ordinary refrigerator or ice box, whereby the excess of cold air or cooling medium produced by the ice in the cooler may be conducted to the interior of the said refrigerator or ice box to cool the same for the preservation of the contents thereof, without decreasing the temperature of or lessening the effects of the ice on the drinking water.

A final object is to provide a neat and attractive water cooler of any desired size or capacity for use in homes, offices, cafes, etc., and of any desired shape, either round, square, triangular, hexagonal or octagonal, and to have any desired number of draw-off cocks or faucets, whereby a plurality of drinking cups may be filled simultaneously with water which has not come into contact with the ice, and which has not been exposed to the atmosphere.

In carrying out the invention, I provide a water cooler having an interior chamber for holding the ice to more thoroughly protect the same, thus resulting in economy in the use thereof, a separate annular chamber surrounding the ice receptacle for holding the water, under constant pressure from the mains, and an outer, annular vacuum chamber, surrounding the water chamber for insulating the water from the outside atmosphere, the entire structure being formed of a single casting of aluminum or some other non-corrosive and non-rusting metal, thus eliminating all necessity for the use of bolts, rivets or other fastening means or soldering, brazing or welding of joints and producing

a structure which is practically indestructible.

A full and complete understanding of the invention may be obtained from a consideration of the following detailed description, taken in connection with the accompanying drawing forming a part of this specification; it being understood that while the drawing shows a practical form of the invention, the latter is not to be confined to strict conformity with the showing thereof, but may be changed or modified so long as such changes or modifications mark no material departure from the salient features of the invention, as specifically pointed out in the appended claims.

In the drawing, in which similar reference characters designate corresponding parts throughout the several figures:

Figure 1 is a perspective view of a water cooler constructed in accordance with the present invention, the table, counter, shelf or other supporting means being omitted;

Figure 2 is a vertical, transverse sectional view through the same;

Figure 3 is a horizontal section, taken on the line 3—3 of Figure 2; and

Figure 4 is a detail, vertical section of the casting comprising the ice, water and vacuum chambers.

In the drawing there is illustrated a cooler which may be considered as of a size and capacity and adapted for use in cafes or other public places, the same being equipped with a plurality of draw-off cocks or faucets.

As shown in Figure 4 of the drawing, the cooler comprises a hollow, shell-like casing in the form of a single casting, preferably of aluminum, and having an outer annular wall 1 completely surrounding the same, an intermediate, annular wall 2 in spaced relation thereto, and an inner, annular wall 3, likewise in spaced relation to the intermediate wall, the spaces between the several walls being preferably equal, though not necessarily so.

The walls 1, 2 and 3 are joined together, at their lower ends, by an integral base plate 4 which completely closes the lower ends of all three chambers thus provided, the inner chamber 5 which constitutes the ice chamber, being open at the top, while the other two annular chambers, i. e. the intermediate

chamber 6 and the outer chamber 7, are closed at the top by an integral, annular wall 8, thus hermetically sealing the two outer chambers except through certain passageways to be described.

The intermediate annular chamber 6 constitutes the water receptacle, and the outer annular chamber 7 constitutes the insulating chamber for protecting the outer wall 2 of the water chamber from the warming influences of the outside atmosphere, the said chamber 7 having the air withdrawn therefrom, so as to provide a vacuum for the purpose, and which, as is well known, serves to maintain the temperature of the enclosed chamber at an even degree, whether the same be high or low, or for heating or cooling purposes.

In order to maintain a constant supply of clean, uncontaminated water to the water chamber 6, an integrally formed sleeve 9 is formed in the casting and extends across the outer chamber 7, near the top thereof, and communicates at the inner end with the water receptacle 6, the said sleeve being internally threaded for the threaded end of a supply pipe 10 which may be tapped into the regular service pipe for the supply of water.

At equally spaced points around the interior walls of the inner or ice chamber 5 and in spaced relation to the bottom or base plate 4, are a plurality of integral, inwardly-directed, radially disposed lugs 11, preferably three in number, which serve to support a metallic disc 12 (preferably formed of aluminum, and having a diameter somewhat less than the interior diameter of the wall 3, so as to provide a dripping space 13 extending entirely around the disc for the water from the ice, which is supported upon the disc 12, to gravitate to the bottom plate. The bottom plate 4 is dished, as at 14, so as to cause the drippage to flow to a central opening 15, into which is screwed a drain pipe 16, which may connect the cooler to a drain pan or sewer, as the case may be, the said pipe having an ordinary goose-neck or trap 17 applied thereto or formed therein, as clearly shown in Figure 1 of the drawing, and which, as is well known, serves to prevent entrance into the cooler of foul air, as in cases where connection is made to a sewer, or of warm air in case a drip pan is used and, in the present instance, the trap 17 further performs the function of preventing the escape of any of the cold air from the ice within the central chamber 5.

In the illustrated form of the device, there are three draw-off cocks or faucets 18 shown, but it will be understood that any number, either more or less, may be used in manufacturing the cooler, the same depending upon the use to which the cooler is to be put. For instance, if the cooler is to be intended for

domestic use, as in an ordinary home, only one faucet would suffice, but in larger coolers of various sizes, two, three or more would be necessary, and the height and diameter of the various chambers would be correspondingly increased to give the necessary capacity.

The faucets 18 may be of ordinary construction and have their threaded nipples 19 screwed into integrally formed sleeves 20 traversing the outer, or insulating chamber 7, adjacent to the base plate 4, the inner ends of the sleeves communicating with the water receptacle 6 and having intermediate, circumferential shoulders 21 adapted to receive and hold a non-corrosive, wire gauze disc 22, which is held against said shoulder by the inner end of the nipple 19 of the faucet.

The water receptacle is adapted to have its lower portion filled with a quantity of charcoal, Tripoli rock or other filtering medium calculated to free the water passing therethrough of any impurities and to soften the same, the said filtering medium, where entering the several sleeves 20, being prevented from passing through the faucets by reason of the wire gauze discs 22, as will be understood.

A lid or cover 23, formed of a hollow casting of the same metal as the body member of the cooler, is adapted to close the upper open end of the ice receptacle 5 and to rest upon the top, annular wall 8. The cover is composed of two sections, the main portion 23 and a stationary portion 24, which latter is adapted to be screwed or otherwise secured to the top annular wall 8 and having hinge members or eyes for coaction with similar eyes formed on the main portion of the cover to form a hinge 25 for permitting the main cover to be swung upwardly for the purpose of supplying the inner chamber 5 with cracked or broken ice, as illustrated.

The cover 23 is provided with a central depressed, hollow portion 26 fitting into the upper end of the chamber 5 to form a tight closure therefor, and the two members of the cover have their marginal peripheries to conform to the shape of the body member, but of greater diameter than the same, and they are hollow and adapted to be evacuated of their air contents to form a vacuum for the same purpose as the chamber 7 of the body member.

To enhance the appearance of the cooler, and to provide an enlarged area within the cover, the top plate thereof is formed with an upstanding enlargement or dome 27 formed integrally therewith and communicating with the same, and at the side opposite the hinge 25, a lifting handle 28 is secured for the purpose of raising the cover.

In order to increase the insulating qualities of the vacuum within the outer, empty chamber 7, an asbestos covering 29 is ap-

plied to the outer face of the outer cylinder or wall 1, and a thin sheet 30 of aluminum or nickel-plated metal is placed over the same, the said covering serving to hold the 5 asbestos in place and serving as an attractive finish to the body of the cooler, the upper end of the covering 30 having a circumferential cornice 31 matching the outer periphery of the lid or cover 23, while the lower end 10 of said covering 30 is formed into a similar shape to form an extended base 32 to add to the appearance of the cooler.

With the connections 10 and 16 properly made to the water supply source and the 15 sewer respectively, and the cooler properly mounted on a suitable support (not shown) with the faucets 18 all closed, the cover 23 is raised and the ice placed within the receptacle 5 and upon the disc 12, the said 20 cover being then tightly closed to exclude the entrance of air into the ice chamber, which is thus preserved in a cold state by the surrounding vacuum chambers in the body member and the cover, thus resulting in great 25 economy in the use of ice. The drippage from the ice is taken care of by the outlet or drain pipe 16, and the water held in the trap 17 prevents the cold air from the ice chamber from escaping and also prevents 30 any warm air or gases from entering the ice chamber to either melt the ice or contaminate the same. As fast as the water is drawn through any one or all of the faucets, the supply is immediately replenished by reason 35 of the pressure within the pipe 10, the filtering medium indicated at 33, in Figure 2 of the drawing, serving to remove all impurities from the water before the same is drawn for consumption.

40 In cleansing the cooler, it is only necessary to disconnect the pipes 10 and 16 therefrom and by inverting the cooler, removing one 45 of the faucets 18, and introducing a hose nozzle or other spray into the sleeve 20 thus vacated, the filtering medium 33 together with any foreign matter or accumulations may be readily flushed and dislodged from within the water chamber 6, and the same thoroughly cleansed and removed therefrom 50 through the open sleeve 9, whereupon fresh filtering material may be introduced through the said sleeve 9, the said faucet re-applied in position within the sleeve 20, the connections 10 and 16 made and the water allowed 55 to flow into the cooler again, such replenishment of the filtering materials being necessary only at long intervals, depending on the condition of the water within the mains.

60 In some instances, especially when the cooler is designed for domestic or family use, it is desirable to utilize the refrigerating capabilities of the device for the purpose of keeping cool the interior of an ice box or refrigerator, without the necessity for daily 65 supplying the same with ice, as is customary.

With the use of the present water cooler, a constant supply of cold water for drinking may be always on hand and foods or liquids advantageously kept or preserved in good condition in a manner to be explained.

70

The bottom wall or plate 4 of the cooler is provided, within the ice chamber 5 with spaced, upstanding, circumferential flanges 34, each surrounding an outlet passage 35 formed in the bottom 4. These outlets are 75 preferably two in number and are at diametrically opposite sides of the central outlet 15 and adjacent to the circumferential wall 3, the upper ends of said flanges 34 being sufficiently raised above the inclined bottom wall 80 4 to prevent any of the drippage from entering and passing out of the passages 35, and when the device is used only as a water cooler, as hereinbefore described, corks or other closures 36 are pushed into the flanges 85 34 to prevent the inlet of air. When, however, the device is adapted for use in cooling an ice box or refrigerator, said corks are withdrawn, and a pair of thin sheet metal tubes are introduced into the openings 35, 90 said tubes having outstanding flanges at their upper ends to rest upon the circumferential flanges 34 to support the tubes, and the latter are placed through an opening 95 formed in the top wall of the ice box or refrigerator and are allowed to extend into the usual ice chamber of said ice box or refrigerator with the device resting upon the top of the same and in covering relation to the aforesaid opening, none of which has, however, been deemed necessary to be illustrated 100 in the drawing. It will be readily understood that the cold air generated by the ice within the receptacle 5 will pass down through the aforesaid tubes depending from the openings 35 and will cause a cooling of the refrigerator without detracting from the cooling effect of the same upon the water within the receptacle 6, and that the same supply of ice serves to keep the drinking water cool as well as the contents of the ice 105 box or refrigerator.

110 From the foregoing it will be seen that a simple, cheaply manufactured and strong and durable cooler has been provided which may be readily formed in a single casting and kept in a sanitary condition, and that the same has no rivets, screws or joints to rust out, the device being neat and attractive 115 in appearance and advantageous for use in homes or public places, there being no necessity for constantly filling the water chamber, or otherwise requiring the offices of an attendant, and that the particular formation and arrangement of the parts renders capable the keeping of the water at a low temperature with a minimum amount of ice.

120 What is claimed is:—

125 1. A water cooler formed of a single casting and comprising an inner, cylindrical 130

chamber closed at the bottom and open at the top and constituting an ice chamber, the upper face of the bottom being dished and provided with a central drain opening for carrying off the drippage, opposite, up-standing circular flanges formed on said bottom having apertures adapted to be plugged or unplugged, and when unplugged to be put in communication with the interior 10 of an ice box, an annular water chamber surrounding the ice chamber and closed at the top and bottom, means for constantly supplying water thereto, means for drawing off the water when desired, an annular 15 vacuum chamber surrounding the water chamber and closed at each end, and a hollow, vacuum lid hinged to the upper, annular walls of the vacuum and water chambers and having a depending portion for fitting 20 into and closing the ice chamber.

2. A water cooler formed of a single casting and comprising an inner, cylindrical chamber closed at the bottom and open at the top and constituting an ice chamber, 25 spaced radial lugs formed within and adjacent to the bottom of said chamber, a removable disc of less diameter than the in-

terior of said chamber and adapted to rest on the lugs to support ice, the upper face of the bottom being dished and provided with a central drain opening for carrying off the drippage from around the periphery of said ice-supporting disc opposite, up-standing circular flanges formed on said bottom having apertures adapted to be 30 plugged or unplugged, and when unplugged to be put in communication with the interior of an ice box, an annular water chamber surrounding the ice chamber and closed at the top and bottom, means for constantly 35 supplying water thereto, means for drawing off the water when desired, an annular, vacuum chamber surrounding the water chamber and closed at each end, and a hollow, vacuum lid hinged to the upper annular 40 walls of the vacuum and water chambers and having a depending portion for fitting 45 into and closing the ice chamber.

In testimony that we claim the foregoing as our own, we have hereto affixed our signatures.

EDWARD A. HAAS.
MACK POSEY.
